FUSE CONSTRUCTION

Henry V. Dryer, Milwaukee, Wis., assignor to
 McGraw Electric Company, a corporation of
 Delaware

Application April 28, 1948, Serial No. 23,711

6 Claims. (Cl. 200—120)

1

This invention relates to a fuse construction and is particularly directed to a current limiting cartridge type of fuse construction. Current limiting cartridge type fuses have frequently been filled with sand or other granular material to provide an extensive condensing and cooling surface, but these constructions have not always proven satisfactory. For example, in certain types of sand filled fuses it has been found that a fulgurite is frequently formed under certain conditions which is conducting at very high temperatures and consequently interferes with the desired or correct action of the fuse. Also, certain types of sand-filled fuses create an excessively high voltage surge on the line when the fuse wire ruptures, which in some cases has caused breakdown or flashover of nearby insulation.

Objects of this invention are to provide a fuse construction in which sand or other granular refractory material is provided at opposite ends of the cartridge type fuse to provide expansion zones for the gases generated by the blowing of the fuse link and to provide extended surfaces which act as cooling and condensing surfaces for the hot gases, and to provide intermediate the portions of sand a material which, when acted upon by the arc, evolves a water vapor or other vapor which chills the arc and also quickly cools any fulgurite that may be formed in the sand and prevents it from reaching a temperature so high that it would become a conductor.

Further objects of this invention are to provide a very simple type of construction in which, though the device is a closed cartridge type of fuse, nevertheless the pressure generated on blowing of the fuse even on heavy short-circuit currents never reaches an excessive or dangerous value.

A still further object of this invention is to provide a current limiting type of fuse which does not develop an excessive voltage surge when the fuse blows.

An embodiment of the invention is shown in the accompanying drawings, in which:

Figure 1 is a longitudinal, sectional view through the cartridge type fuse.

Figure 2 is a chart showing the effect of different per cents of bauxite upon the ratio of the actual maximum current, when rupture occurs, to the maximum available current.

Figure 3 is a chart showing curves illustrating the effectiveness of the bauxite and sand arrangement in reducing the arc length—equivalent to length of fuse wire—required to clear in an

2

ordinary sand-filled fuse when both are operating under the same circuit conditions.

Any suitable type of cartridge type fuse can be employed. For instance, the cartridge fuse may be of the type disclosed in my copending application Serial No. 11,132, filed February 26, 1948, for Fuse Constructions, which has issued as Patent No. 2,490,950, dated December 13, 1949. This cartridge type of fuse is illustrated in Figure 1 and may comprise a Bakelite or other outer tubular casing 1 provided with a clear acrylic transparent plug 2 screwed therein and with end conducting caps 3 and 4. It is understood that the indicator shown in Figure 1 is not essential to the proper operation of the fuse in clearing the circuit. The end conducting caps are in electrical connection with end fittings 5 and 6 between which a ribbed, ceramic supporting rod 7 is held. This ceramic supporting rod may be notched as indicated at 8 to position a portion of the fuse link 9 wrapped therearound immediately adjacent the inner end of the transparent plug. This construction, of course, can be varied as will be seen as the description proceeds, but is merely detailed as one of the possible forms that the invention may take. Sections of sand 10 and 11 are located adjacent opposite ends of the interior of the tubular casing 1 and a section of bauxite 12 is located approximately centrally between the two sand sections 10 and 11. Many other granular or granulated refractory materials, as for example quartz, silica, alumina, or magnesia may be used in place of the sand. A quartz or silica sand and bauxite are the most practical combination of materials from the standpoint of efficiency of operation as well as low cost. The ends of the fuse link 9 are attached in any suitable manner, not shown, to the fittings 5 and 6. Obviously, other types of fuse constructions could be employed. For example, with lower voltage fuse links it would not be necessary to use the ceramic supporting rod 7, but on high voltage fuse links of small diameter it is found more convenient to support the fuse link on the ceramic rod 7. However, this invention is primarily concerned with the arrangement of the bauxite and the sand, granular quartz, or other granular refractory material.

It has been found that when the fuse link blows, that it almost invariably ruptures initially in the region which is surrounded by bauxite. On very high currents the initial rupture point is not discernible since the fuse wire melts almost instantaneously along its entire length. The sand sections 10 and 11 provide expansion areas

for the gases liberated upon blowing of the fuse link and also provide vast or extended condensing and cooling surfaces. However, the bauxite has a predominant effect in that it liberates water vapor which tends to chill and thus interrupt the arc and at the same time cools the sand and prevents the sand from ever reaching a conducting state due to complete fusion at high temperature. In other words, if a fulgurite is formed in the sand, the water vapor from the bauxite quickly chills this fulgurite and prevents it from reaching a temperature so high that it would become a conductor and thus support the arc and thus cause failure of the device.

Figure 2 shows the effect of variations in the per cent of bauxite on the current limiting ability of the fuse. The abscissa indicate the per cent of bauxite on the basis of the per cent of the total arc length, that is to say, on length of arc in the bauxite area in Figure 1 to the total arc length between the fittings 5 and 6. The ordinates represent the ratio of the actual value to which the current is limited by the fuse when rupture occurs to the maximum available current. The curve is typical of a fuse embodying the arrangement of materials shown in Figure 1.

It will be seen that the greatest current limitation is obtained when approximately thirty per cent or less of bauxite is used.

It is possible to construct either an all-sand or an all-bauxite cartridge type of fuse that will operate satisfactorily under certain conditions. However, either material when used alone imposes certain limitations or undesirable features. For example, an all-sand fuse creates very little internal pressure and is very effective in limiting the fault current, but frequently causes an excessively high voltage surge at the time of rupture. On the other hand, an all-bauxite fuse results in a relatively low and inconsequential voltage surge but is not as effective in limiting the fault current and at high currents produces rather high internal pressures at the time of rupture.

Thus by using a construction embodying the arrangement illustrated by Figure 1, the designer, by varying the percentage of the materials involved, may construct a fuse having nearly any combination and degree of the above characteristics desired. For example, a fuse construction of this type containing approximately twenty per cent of bauxite is a practical compromise combining the most desirable features for general use in the industry.

Figure 3 shows a chart in which curves A and B show a typical relationship between the minimum arc length required to clear and the system voltage for sand as indicated by the curve A and for sand plus twenty per cent bauxite as indicated by the curve B. It will be seen that the combination of sand with twenty per cent bauxite will clear in substantially half the minimum length as that required for sand alone.

It will also be seen from reference to Figure 2, that the fuse construction limits the short-circuit current to a value well below the maximum available current, particularly so where twenty-five to thirty per cent or less of bauxite is used.

The bauxite remains non-conducting even at high temperatures and serves the highly useful purpose of evolving a quantity of chilling water vapor as previously described. Preferably, the bauxite is a fine powdered material and the sand is a clean, fine grained quartz or silica sand.

It has been found that cartridge type fuses constructed in accordance with this invention do not allow the internal pressure to rise to a dangerous point even when blown under heavy short-circuit conditions. It has been found also that these cartridge type fuses, whether constructed in the exact form shown in Figure 1 or in some other form, can be very cheaply manufactured provided the bauxite and sand are associated and used in the manner indicated. These relatively cheap cartridge type fuses are intended to be discarded after blowing and to be replaced with new cartridge type assemblies.

Although this invention has been described in considerable detail, it is to be understood that such description is intended as illustrative rather than limiting, as the invention may be variously embodied and is to be interpreted as claimed.

I claim:

1. A fuse construction comprising a tubular outer casing, terminals adjacent opposite ends thereof, a fuse link extending through said casing and electrically connecting said terminals, bauxite within said casing adjacent an intermediate portion of said fuse link, and sand within said casing on opposite sides of said bauxite.

2. A fuse construction comprising a tubular outer casing having terminals adjacent opposite ends, a fuse link within said casing electrically connecting said terminals, bauxite within said casing and granular refractory material within said casing, said bauxite and granular refractory material being in contact with said fuse link and said granular refractory material arranged to provide extensive cooling and condensing surfaces for the gases and vapors incident to rupture of said fuse link.

3. A fuse construction comprising a tubular outer casing, terminals adjacent opposite ends thereof, a fuse link extending through said casing and electrically connecting said terminals, bauxite within said casing adjacent an intermediate portion of said fuse link, and sand within said casing on opposite sides of said bauxite, said bauxite being not more than approximately thirty per cent of the total length of said sand and bauxite as measured along the active length of said fuse link.

4. A fuse construction comprising a tubular outer casing, terminals adjacent opposite ends thereof, a fuse link electrically connecting said terminals and extending through said casing, a cooling agent including bauxite located within said casing adjacent an intermediate portion of said fuse link, and a granular refractory substance within said casing and located on opposite sides of said bauxite and arranged to provide extensive cooling and condensing surfaces for the gases and vapors incident to rupture of said fuse link.

5. A fuse construction comprising a tubular outer casing having terminals adjacent opposite ends, a fuse link within said casing electrically connecting said terminals, bauxite within said casing and sand within said casing, said bauxite and sand being in contact with said fuse link and said sand arranged to provide extensive cooling and condensing surfaces for the gases and vapors incident to rupture of said fuse link.

6. A fuse construction comprising a tubular outer casing having terminals adjacent opposite ends, a fuse link within said casing electrically connecting said terminals, powdered bauxite within said casing and granular refractory material within said casing, said powdered bauxite

and granular refractory material being in contact with said fuse link and said granular refractory material arranged to provide extensive cooling and condensing surfaces for the gases and vapors incident to rupture of said fuse link.
